Leonard J. Worden

UNITED STATES PATENT OFFICE.

LEONARD J. WORDEN, OF UTICA, NEW YORK.

IMPROVEMENT IN CAST-IRON BOTTOMS FOR TEA-KETTLES.

Specification forming part of Letters Patent No. 38,780, dated June 2, 1863.

To all whom it may concern:

Be it known that I, LEONARD J. WORDEN, of Utica, in the county of Oneida and State of New York, have invented a new and Improved Mode of Constructing Cast-Iron Bottoms for Sheet-Metal Vessels; and I do hereby declare that the following is a full and exact description thereof, reference being had to the accompanying drawings, and to the letters of reference marked thereon.

The nature of my invention consists in providing a cast-iron bottom for tea-kettles, wash-boilers, and other sheet-metal vessels, which, by reason of their peculiar construction and mode of connection, forms a superior article of manufacture.

To enable others skilled in the art to make and use my invention, I will proceed to describe its construction.

Figure 1 is a perspective view of a tea-kettle with one-half the bottom cut away to show its construction.

A represents the cast-iron bottom; B, a narrow rim or band of sheet metal; C, a raised projection of the bottom cast to and around the lower edge of the band, so as to unite and form a water-tight joint. The cylinder part of the vessel D is then placed over and outside the band B and connected together by soldering on the inside, with or without a seam; or, if preferred, the cast-iron bottom may be cast to and around the lower edge of the cylinder composing the body of the vessel, as shown in the transverse sectional view at A, Fig. 2, forming only one piece without any soldering, which is simply a wide band, instead of the

narrow, extending upward sufficiently high to form the side or body of the vessel, either way making a perfectly water-tight joint.

It is evident that this method of making cast-iron bottoms may be applied to any of the various kinds of sheet metal that can be used in constructing either the body of the vessel or narrow band when united with the bottoms as described; also, that the cylinder or body of the vessel may be placed either outside or inside of the band without changing the nature of the invention.

Having thus described my invention, its advantages over the common mode will be apparent, in that it enables me to substitute cast-iron for copper and other expensive sheet metal, thus reducing the cost of manufacture, while I am enabled to produce a better and more durable article than has heretofore been made.

I am aware that coal-scuttles have been made with cast-iron bottoms by riveting the parts together. I do not, therefore, broadly claim a cast-iron bottom for sheet-metal vessels, neither do I claim uniting or casting two metals together, as in the case of anvils, vise jaws, frogs for railroads, car-wheels, &c.; but I claim as a new article of manufacture—

Making the bottoms of tea-kettles of cast-iron by uniting it to and with the body of the vessel in the manner and for the purpose as herein described and set forth.

LEONARD J. WORDEN.
